UNITED STATES PATENT OFFICE

2,161,647

HYDRAULIC MACHINE

Grant C. Whisler, York, Pa., assignor to S. Morgan Smith Company, York, Pa., a corporation of Pennsylvania

Application March 15, 1938, Serial No. 195,996

3 Claims. (Cl. 253—148)

This invention relates to improvements in hydraulic machines and more particularly to hydraulic turbines of the type wherein the blades of the runner are adjustable to vary their angle 5 and the area of the water opening through the runner to correspond with the angle and opening of the wicket gates or guide vanes which control the admission of water to the runner.

An object of the invention is to provide an 10 improved adjustable blade hydraulic turbine in which the mechanism for operating the runner blade actuating means is mounted in the shaft of the runner in such a manner as to be accessible for repair or adjustment without the necessity of disassembling the turbine.

Another object of the invention is to provide an improved adjustable blade hydraulic turbine 15 in which the runner shaft is formed with two semi-cylindrical sections which are constructed 20 and detachably connected together in such a manner that the mechanism within the runner shaft for operating the runner blade actuating means is supported from only one of the sections 25 of the shaft.

Another object of the invention is to provide an improved runner shaft for adjustable blade hydraulic turbines in which means are provided for circulating currents of air through the shaft in order to prevent overheating of the runner 30 blade operating mechanism within the shaft.

The invention consists in the novel specific details of construction and combination of elements hereinafter described and claimed.

In the accompanying drawings: 35 Figure 1 is a side elevation, partly in section, of a hydraulic turbine having a runner of the adjustable blade type and embodying a runner shaft according to the present invention;

Fig. 2 is an enlarged vertical section of the 40 lower end of the runner shaft, showing the construction of the parts within the hub of the runner;

Figs. 3, 4 and 5 are vertical sections on an enlarged scale of the mechanism at the upper 45 end of the runner shaft for operating the runner blade adjusting means;

Fig. 6 is a horizontal section taken on the line 6—6 of Fig. 3;

Fig. 7 is a horizontal section taken on the line 50 7—7 of Fig. 4;

Fig. 8 is an elevation of one of the sections of the upper portion of the runner shaft, showing the manner in which the mechanism for operating the runner blade actuating means is supported 55 therein, parts being omitted; and

Fig. 9 is a detail side elevation of the upper portion of the runner shaft.

In my application for Letters Patent filed in the United States Patent Office February 17, 1938, Serial No. 191,095, for Hydraulic machine, now Patent No. 2,132,504, dated October 11, 1938, there is described and claimed mechanism for controlling the operation of the runner blades. The present invention relates to structure shown but not claimed in the above referred to prior 10 patent application.

Referring to the drawings, and especially to Fig. 1, the improved hydraulic turbine comprises a casing 11 which forms a peripheral water inlet in which are mounted an annular series of movable wicket gates 12 and an annular series of stationary guide vanes 13, the guide vanes surrounding the wicket gates.

Projecting from the wicket gates 12, are shafts 14 which are journaled in suitable bearings carried by the casing 11 and terminate a suitable distance thereabove.

The wicket gates 12 are adapted to be rotated simultaneously into different angular positions to control the flow of water into the hydraulic turbine in a well-known manner, and for this purpose the upper ends of the shafts 14 are usually provided with gate operating arms 15 which are fixed to said shafts and operatively connected to a gate adjusting ring 16.

The gate adjusting ring 16 is connected by links 17 to a shaft 18 which is usually vertically disposed, as shown at the right in Fig. 1, the shaft 18 being operatively connected to a governor mechanism (not shown) operable by variations in load on the turbine.

The lower end of the casing 11 forms an axially directed chamber 22 in which the runner 23 operates.

As shown in Fig. 2, the hub of the runner 23 is fixed to the lower end of a hollow or tubular shaft 24 which extends upwardly through the casing in the usual manner.

The upper end of the runner shaft 24 is connected to the lower end of a cylindrical casing 40, the upper end of said casing being connected to the shaft 25 of an electric generator 26 which is mounted in superposed position above the hydraulic turbine, as shown in Fig. 1.

Any suitable type of setting may be used, a concrete setting 27 being shown in the present instance. This setting forms a scroll case 28 which surrounds the turbine inlet and is connected to receive water from a flume or other source of supply. The portion of the setting 55

below the runner forms a draft tube 29 into which the water is discharged. The electric generator 26 may rest on top of the setting as shown.

As shown in Fig. 2, a suitable number of blades 30 are rotatably supported in the hub of the runner 23 and project radially therefrom.

The inner end of each blade 30 is formed with a trunnion 31 which is journalled in bearings 32 and 33 supported in the hub. The construction is such that the blades are rotatable into different angular relationships with the axis of the runner.

Means are provided for simultaneously rotating all of the blades 30 and for maintaining them in equal angular relationship, such means comprising preferably an arm 34 rigidly fixed on the trunnion 31 of each blade and links 35 which pivotally connect each arm 34 to a cross head 36. The cross head 36 is guided to reciprocate in a direction axially of the runner by guide pins 37 which are mounted in the hub of the runner in the manner shown in Fig. 2.

It will be understood that the relative positions of the blades 30 govern the area of the water passages or openings between the blades, and that when the blades are rotated, the area of the water passages is increased or decreased depending upon the direction in which the blades are moved.

30 As shown in Fig. 1, a cap 38 is bolted or otherwise removably secured to the lower end of the hub of the runner 23. Since the hub of the runner is otherwise enclosed and the hub is hollow, the cap 38 provides a closed chamber or reservoir for containing a supply of grease for lubricating the various working parts of the mechanism contained within the hub of the runner.

40 In the usual construction of hydraulic turbines the runner shaft is made of sufficient length so that said shaft can be bolted directly to the lower end of the generator shaft. However, in the present instance, the shaft 24 is made comparatively short so that the elongated cylindrical casing 40 can be interposed between the shaft 24 and the generator shaft 25. The casing 40 encloses elements, to be hereinafter described, for operating the runner blade mechanism within the hub of the runner 23, and said casing is adapted to be bolted to the runner shaft 24 and to the generator shaft 25 and thereby constitute a rotary portion of the main shaft of the turbine. The casing 40 is composed of two vertically divided semi-cylindrical sections 140 and 55 141, which sections are adapted to be bolted together at intervals throughout their length, as indicated at 142 in Figs. 3, 4, 6 and 7.

60 The casing 40 is constructed in such a manner that the elements contained therein can be mounted on one half or one section of the casing so that the other half or section of the casing can be removed without dismantling any part of the turbine, the generator, shafts and motor operating mechanism. In this way, inspection, adjustment and replacement of the parts within the casing 40 can be readily accomplished in a minimum amount of time.

65 In the present instance the section 140 of the casing 40 will be referred to as the mechanism carrying portion of said casing, and the section 141 will be referred to as the cover.

70 Since openings are formed in the casing, these openings are also adapted to be closed by covers or plates so that the exterior surface of the casing will be smooth, as shown in Fig. 1.

As shown in Figs. 3, 4, 6, 7, 8 and 9, the outer wall of the casing is formed with a plurality of openings 143, so that the bolts 142 will be accessible to a wrench or other tool.

Covering the openings 143 are plates 144 which are detachably secured to the outer wall of the casing 40 by means of screws 145 (see Figs. 6, 7 and 9).

The upper portion of the shaft 24 is enlarged, as indicated at 41, Figs. 4 and 5. This enlarged portion of the shaft 24 is secured to the lower portion of both sections of the casing 40 by a plurality of bolts 42, as shown in Figs. 4, 5 and 7.

The lower portion of the generator shaft 25 is formed with a flange 43 which is secured to the upper portion of the casing 40 by bolts 44, as shown in Fig. 3.

In this way rotation of the runner shaft 24 will be transmitted to the generator shaft 25 by the casing 40.

20 Disposed within the casing 40 is an electric motor 45 which is adapted, through mechanism to be hereinafter described, to operate the runner blade adjusting mechanism in the hub of the runner 23.

25 Since the runner blades are adjusted by slowly moving the cross head 36 either upwardly or downwardly, and since it is of advantage to employ an electric motor of standard design, which motors usually have a comparatively high 30 speed, it is necessary to provide means in the mechanism which is employed to operatively connect the electric motor with the cross head 36, for reducing the speed from the motor sufficiently to effect the desired slow movement of the cross 35 head 36.

As shown in Fig. 2, the cross head 36 is bolted or otherwise fixed to the lower end of an operating rod 46 which extends upwardly through the hollow 40 runner shaft 24.

40 As shown in Fig. 5, the upper end of the rod 46 is fixed to an internally threaded sleeve 47 which is slidably mounted in the bore of the runner shaft 24.

45 Fitted to the sleeve 47 is a screw 48, which is connected to the driven member 49 of a speed reducer 50.

50 As shown in Figs. 4 and 7, the speed reducer comprises a driving member in the form of a shaft 51, and the driven member 49.

55 The driving member or shaft 51, which is connected to the shaft 52 of the motor 45 by a coupling 53, has an eccentric 54 thereon which supports a ball bearing or other anti-friction bearing 55.

55 The outer member or race of the ball bearing 55 is surrounded by a series of radially disposed plungers 56. The inner ends of the plungers 56 bear on the outer race of the bearing 55 and the outer ends of said plungers are arranged to cooperate with teeth 57 formed concentrically within the outer or stationary member 58. Both ends of the plungers 56 are bevelled, and the teeth 57 are bevelled.

60 The number of teeth 57 differs from the number 65 of plungers 56 so that rotation of the eccentric 54 will cause the plungers 56 to be forced outwardly in succession around the circular series of teeth 57 and in consequence will cause the plungers to creep around within the stationary member 58.

70 The plungers 56 are guided to reciprocate in a member 59 which is fixed to the driven member 49 by pins 60 so that the creeping motion of said plungers around the toothed interior of the sta- 75

tionary member 58 will be transmitted to the driven member 49. The motion of the driving member 58 is thus transmitted to the driven member 49, but at a great reduction in speed ratio.

5 The speed reducer 50 is mounted between upper and lower supporting members 61 and 62, respectively, which are fixed within the casing 40 by bolts 63 attached to the enlarged portion 41 of the runner shaft 24, as shown in Figs. 4 and 8.

10 The upper portion of the supporting member 61 is formed with a flange 161, upon which is mounted a flange 162 of the motor 45. The flanges 161 and 162 are secured together by bolts 163, as shown in Fig. 4. In this way the motor 45 is supported from the main runner shaft 24.

15 Upper and lower roller thrust bearings 64 and 65 are, respectively, provided for the speed reducer 50, and above the upper thrust bearing 64 there is a ball bearing 66. The roller thrust bearings are adapted to carry the forces imposed on the operating rod 46 by the runner blades.

20 The driving member of the speed reducer 50 is connected to the armature or other rotating part (not shown) of the motor 45, so that the speed reducer will be actuated by said motor.

25 Since the driven member 49 of the speed reducer 50 and the screw 48 are directly connected together, the rod 46 will be operated by the sleeve 47 to effect changes in the angular positions of the runner blades.

30 For the purpose of indicating the relative positions of the runner blades, at a convenient point the runner shaft 24 is formed with an elongated slot 68 (see Figs. 1 and 5).

35 Disposed within the slot 68 is a pointed pin 69 which is fixed to the upper portion of the operating rod 46. In the present instance the pin 69 is shown as being carried by the sleeve 47.

40 As shown in Fig. 1 the exterior of the runner shaft 24 adjacent to the slot 68 carries suitable marks for indicating the several angles of runner blade positions, as determined by the position of the pointed pin 69.

45 Preferably the electric motor 45 is a three-phase alternating current induction motor which is adapted to be supplied with electric current from a main power line in such a manner that the motor will operate in either direction.

50 When the motor 45 operates in one direction the screw 48 will, through the sleeve 47, cause a rectilinear movement of the rod 46 in one direction, and when the motor 45 operates in the other direction, the rod 46 will be moved in the opposite direction, due to the reversed movements imparted 55 to the screw 48 by the motor.

55 As shown by the arrow, Fig. 2, when the rod 46 moves upwardly, the runner blades 30 are moved towards closed position, and when the rod 46 moves downwardly in a direction opposite to the arrow, Fig. 2, the runner blades are moved toward open position.

60 The mechanism for controlling the operation of the motor 45, which is shown and described in detail in my United States Letters Patent No. 65 2,132,504, dated October 11, 1938, includes a self-synchronous motor 71.

65 As shown in Figs. 3 and 8, the motor 71 has a spur gear shaft 78 carrying a gear 79 which is in meshing relationship with a gear 80 fixed 70 to the shaft 52 of the motor 45.

75 The motor 71 is bolted or otherwise secured to the section 140 of the casing 40, as indicated at 146 in Figs. 3 and 6.

The casing 40 carries a plurality of collector rings 81 which are electrically connected to the

motors 45 and 71. The collector rings are, respectively, engaged by a plurality of brushes 101, carried by a bracket 109 suspended from the generator 26. The brushes 101 in turn are connected to a corresponding number of electric conductors so that electric current will be supplied to the motors 45 and 71 in the manner described in detail in my other patent application heretofore referred to.

As shown in Figs. 6, 7 and 9, the casing 40 may have lower and upper inlet and outlet vent openings 147 and 148, respectively, formed therein for inducing currents of air to flow through the interior of the casing when the runner is in operation, so as to prevent overheating of the elements of the apparatus within the casing. In Fig. 6 the arrow indicates that the direction of rotation of the runner shaft is clock-wise. As shown in Fig. 7, the wall 149 at the inlet vent opening 147 is so formed that, during rotation 20 of the runner, air will be directed by said wall towards the interior of the casing. As shown in Fig. 6, the wall 150 at the outlet opening 148 is so formed as to permit the air to pass outwardly from the interior of the casing. Preferably the vent openings 147 and 148 are formed in the cover plate 144.

When it is desired to inspect or adjust the elements within the casing 40, the cover plates 144 are first removed, thereby exposing the bolts 30 142. The nuts of these bolts can next be removed from the threaded stems of the bolts so as to uncouple the cover section 141 from the section 140 of the casing. The section 141 can then be removed and the parts will then have 35 the appearance illustrated in Fig. 8, in which it will be noted that the motors 45 and 71 and the speed reducer 50 and associated parts are readily accessible.

As shown in Fig. 3, the collector rings 81 are 40 preferably mounted on vertically disposed bars 89 which are detachably connected to the upper portion of the casing 40 by screws 151. Only one bar 89 is shown, but it will be understood that a suitable number of these bars can be arranged around the casing 40 to rigidly support 45 the collector rings.

When the parts of the runner shaft are being assembled and disassembled it is the practice to secure the bars 89 to the casing at the completion 50 of the assembly operation and to detach the bars 89 from the casing 40 at the beginning of the operation of disassembling the casing. When the bars 89 have been detached from the casing, the collector rings and the bars can be 55 moved upwardly a distance sufficient to expose the upper portion of the casing. For this reason the collector rings are not shown in Figs. 8 and 9.

Having thus described my invention, what I claim is:

1. In a hydraulic turbine, a runner having blades movable into different angular positions, mechanism within the hub of the runner for adjusting the runner blades, a hollow runner shaft connected to the hub of the runner, a rod disposed within said shaft and operatively connected to the runner blade adjusting mechanism within the hub of the runner, a hollow casing secured to the upper end of said runner shaft and having two semi-cylindrical vertically divided sections detachably connected together, and mechanism disposed within said casing and mounted on only one of the sections thereof and operatively connected to said rod for operating said rod.

2. In a hydraulic turbine, a runner having blades movable into different angular positions, mechanism within the hub of the runner for moving said blades, a hollow runner shaft connected to the hub of the runner, said runner shaft comprising a casing having two semi-cylindrical vertically divided sections detachably connected together, and means within said shaft connected to the runner blade operating mechanism within the hub of the runner for operating said mechanism, said operating means being supported solely by one section only of said shaft, whereby the other section of said shaft can be removed without disturbing the operating means within the shaft.
3. In a hydraulic turbine, a runner having blades movable into different angular positions, mechanism within the hub of the runner for

moving said blades, a hollow runner shaft connected to the hub of the runner and having means mounted therein and connected to the runner blade operating mechanism for actuating the same, said runner shaft being composed of two vertically divided semi-cylindrical sections, bolts for detachably connecting the sections together, recesses formed in the shaft for said bolts, said shaft having lower and upper inlet and outlet vent openings, respectively, 10 formed therein, a plate covering said recesses and said vent openings, and means formed on said plate and disposed within said vent openings for directing currents of air towards the interior of said shaft through one opening and outwardly of the shaft through the other opening. 15

GRANT C. WHISLER.
